UNITED STATES PATENT OFFICE.

MOSES M. MARCUSE, OF RICHMOND, VIRGINIA, ASSIGNOR TO THE HASKER & MARCUSE MANUFACTURING COMPANY, OF SAME PLACE.

CIGARETTE-BOX.

SPECIFICATION forming part of Letters Patent No. 629,263, dated July 18, 1899.

Application filed November 15, 1898. Serial No. 696,550. (No model.)

To all whom it may concern:

Be it known that I, MOSES M. MARCUSE, a citizen of the United States, residing at Richmond, in the county of Henrico and State of

5 Virginia, have invented certain new and useful Improvements in Cigarette-Boxes, of which the following is a specification, reference being had therein to the accompanying drawings, in which—

10 Figure 1 is a perspective view of my improved box, partly broken away at its lower end; Fig. 2, a vertical section of the box, showing the manner of forcing out the contents; Fig. 3, a similar section at a right angle to the line on which the former section is taken; Fig. 4, a transverse section of a box filled with cigarettes.

15 This invention relates to that class of cigarette-boxes in which the cigarettes rest end- wise upon a bottom which is movable within the casing, the casing being closed at its upper end by a hinged cover, which is adapted to swing open by pressure from the upper ends of the cigarettes when the movable bottom is forced upward, as more fully herein- 20 after set forth.

25 Referring to the drawings by letters, *a* designates the main casing, which in the present instance is oblong in cross-section and of a size to receive five transverse rows of cigarettes, with two cigarettes in each row; but it is obvious that it may be varied in size and shape. The upper end of the casing is closed by a hinged cover *b* and its lower end by a 30 movable bottom *c*, which rests loosely upon a flange *d*, formed on the lower end of the case *a* and extending entirely around the bottom. This flange thus supports the bottom *c*, but at the same time exposes nearly its entire 35 lower surface, so that said bottom can be manipulated from below by the fingers. The bottom *c* consists simply of a flat plate made to nicely fit the interior of the case all around. To assist in guiding it in its vertical move- 40 ments, it may be provided with ears *e*, which extend upward and are tapered upward.

45 These ears rest flat against the inner surfaces of the walls of the case and are so disposed along the edges of the bottom that they will 50 project upward between the adjacent round- ed surfaces of the cigarettes between where

the cigarettes come in contact with the interior of the case, so that said ears will avoid coming in contact with and injuring the wrappers of the cigarettes.

55

It will be observed that by my invention a light strong sheet-metal box may be made that may be conveniently carried in a small pocket and which will preserve the cigarettes from injury. Ready access is had to the cigarettes by simply pressing upward upon the bottom plate through the opening in the bottom of the case, as shown in Figs. 2 and 3, the hinge-cover being thrown open automatically by the pressure of the upper ends 60 of the cigarettes. The cigarettes may be forced up evenly, as shown in Fig. 2, or they may be forced up unevenly by tilting the bottom slightly, as shown in Fig. 3, the tapered ears *e* being of insufficient height to prevent 65 this tilting movement. The advantage in thus forcing the cigarettes up unevenly is that they will be presented singly or in couples, thereby making it easier to withdraw them singly from the box, which is obviously ad- 70 vantageous in view of the fact that they are always consumed singly and the further fact that it is not uncommon that the projecting ends of the cigarettes are injured in removing them singly from the boxes now in ordinary use, as they have to be separated before 75 they can be withdrawn, this being especially the case when the box is full.

80 A very essential advantage arising from the use of a bottom consisting of a simple plate 85 is that the cigarettes are permitted to bear directly against the inner surfaces of the walls of the boxes their entire length, whereby the cigarettes will be supported throughout their length and will not bear against any projec- 90 tions or shoulders at any point between their ends, whereby they will be preserved against injury not only when the box is full, but also when partly empty, which would not be the case were the movable bottom provided with 95 upward-extending flanges coming in contact with the sides of the cigarettes.

100 It will be observed that the ears at the ends of the bottom are not sufficiently high to prevent it being tilted endwise, as in Fig. 3; but owing to the narrow width of the box the ears at the side edges of the bottom will prevent

it tilting sidewise, whereby the bottom will be guided vertically even though it be tilted endwise during its vertical movements.

Having thus fully described my invention, what I claim, and desire to secure by Letters Patent, is—

1. A cigarette-box consisting of a casing having its upper end provided with a movable cover and its lower end open and provided with an inward-extending flange, and a bottom inclosed within the casing and resting loosely on said flange, said bottom consisting of a plate fitting the interior of the box and movable vertically therein independently of the cover and adapted to be tilted.

2. A cigarette-box consisting of a casing having its upper end closed by a hinged cover and its lower end open, provided with an inward-turned flange, and a bottom inclosed in the casing and resting on said flange and consisting of an unflanged plate provided with upward-turned tapering ears at points along

its side edges, said plate being movable vertically independently of the cover, as and for the purpose set forth.

3. A cigarette-box consisting of a casing having its upper end provided with a cover and its lower end open and provided with an inward-extending flange, and a bottom inclosed within the casing and resting loosely on said flange and movable vertically therein independently of the cover and adapted to be tilted endwise, and means carried by the bottom for guiding the plate vertically against the sides of the casing and preventing it tilting sidewise.

In testimony whereof I hereunto affix my signature, in the presence of two witnesses, this 5th day of November, 1898.

MOSES M. MARCUSE.
